UNITED STATES PATENT OFFICE.

EDWIN L. BERG, OF SALINA, KANSAS.

FLOWER-SUPPORT FOR CASKETS.

No. 917,839.

Specification of Letters Patent.

Patented April 18, 1909.

Application filed July 17, 1908. Serial No. 444,092.

To all whom it may concern:

Be it known that I, EDWIN L. BERG, citizen of the United States, residing at Salina, in the county of Saline and State of Kansas, have invented certain new and useful Improvements in Flower-Supports for Caskets, of which the following is a specification.

This invention comprehends certain new and useful improvements in burial apparatus, and the object of the invention is an improved stand which is designed to be applied to a casket to support the flowers customarily placed thereon, which is adapted to be sustained in a peculiar manner in the mouth of the grave, to temporarily close the same when the casket is lowered into position therein, and which is susceptible of being adjusted for use in connection with caskets of different sizes, and is capable of being telescoped when not desired for use, so as to occupy a comparatively small space and be conveniently handled.

With this and other objects in view that will more fully appear as the description proceeds, the invention consists in certain constructions and arrangements of the parts that I shall hereinafter fully describe, and then point out the novel features thereof in the appended claims.

For a full understanding of the invention and the merits thereof, and to acquire a knowledge of the details of construction, reference is to be had to the following description and accompanying drawings, in which:

Figure 1 is a plan view of my improved flower stand; Fig. 2 is a longitudinal section thereof on the line 2—2 of Fig. 1; Fig. 3 is an enlarged detail sectional view on the line 3—3 of Fig. 1; Fig. 4 is a similar view on the line 4—4 of Fig. 1; Fig. 5 is a plan view showing the parts of the stand telescoped; Fig. 6 is a side elevation showing the stand applied to a casket; and, Fig. 7 is a sectional view illustrating the application of the stand to a grave.

Corresponding and like parts are referred to in the following description and indicated in all the views of the drawings, by the same reference characters.

My improved stand or flower-supporting framework embodies a central portion consisting of a plurality of substantially parallel hollow longitudinal bars 1 and pairs of transverse sleeves 2 rigidly secured to the bars near the respective ends thereof. In order to extend the framework longitudi-

nally, I provide a plurality of rods 3 which have their inner ends mounted in the longitudinal bars 1 and are arranged to telescope therewith, with their outer ends secured to 60 and held in properly spaced relation by transversely disposed hollow end bars 4. 5 designates the corner bars which have transversely disposed arms mounted in and arranged to telescope with the respective end bars 4, and 65 which have their other or longitudinal arms telescoping with substantially hollow longitudinal side bars 6. These side bars have a sliding connection with and are supported upon arms 7 which are mounted at their 70 inner ends in the respective sleeves 2 and have their outer ends arranged to extend laterally beyond the side bars 6 and preferably crooked, as clearly illustrated in Fig. 7.

In the practical use of my improved stand, 75 the latter is placed upon the casket, being first adjusted to the size thereof, and the flowers are placed upon the stand in the customary way. When it is desired to remove the lid at the head of the coffin, it obviously 80 becomes necessary to shift the flower-supporting framework longitudinally thereof, so that one end projects beyond the foot of the coffin, as shown. In order to support this end, I provide the same with legs 8 that are 85 pivotally connected at one end to outwardly disposed lugs 9 formed upon the corresponding corner bars 5, and which are adapted to extend downwardly to rest upon the floor or other supporting surface, as shown, said legs 90 being susceptible of being swung upwardly when not desired for use, and having their free ends arranged for engagement with spring catches 10 carried by the side bars 6, so as to be maintained securely in inoperative 95 position. Before the casket is lowered into the grave, the arms 7 are extended laterally, so as to project beyond the side bars 6 and be adapted to bear against the surface of the ground on opposite sides of the grave, 100 or to engage the coping or rim, if the latter is constructed with such, and thus suspend the flower-supporting framework in the mouth of the grave to temporarily close the same as the casket is lowered into position. 105

From the above description, in connection with the accompanying drawings, it will be apparent that I have provided a simple, durable and efficient construction of flower stand which is adapted to support flowers in the 110 mouth of the grave, to screen the casket from view as it is lowered into position therein,

which is susceptible of being telescoped so as to be substantially the same in size as the central portion of the framework, and which consists of comparatively few parts that may 5 be easily and cheaply manufactured and readily assembled.

Having thus described the invention, what I claim is:

- 10 1. A flower stand of the character described, comprising a supporting framework designed to rest upon a casket, and means carried by the framework for sustaining the same in the mouth of a grave, upon the lowering of the casket therein.
- 15 2. A flower stand of the character described, comprising an extensible framework designed to rest upon a casket, and means carried by the framework for sustaining the same in the mouth of a grave, upon the lowering of the casket therein.
- 20 3. A flower stand of the character described, comprising a supporting framework designed to rest upon a casket and embodying a central portion, means carried by the central portion for extending the same laterally and longitudinally, and means also carried by the framework for sustaining the same in the mouth of the grave, upon the lowering of the casket therein.
- 25 4. A flower stand of the character described, comprising a supporting framework designed to rest upon a casket and embodying a central portion and side and end extensions carried by the central portion, and arms also carried by the central portion and adapted to project beyond the margin of the framework, as and for the purpose specified.
- 30 5. A flower stand of the character described, comprising a supporting framework 40 consisting of a central portion embodying a

plurality of substantially parallel hollow longitudinal bars, rods mounted at their inner ends in the longitudinal bars and arranged to telescope therewith, transversely disposed end bars secured to the outer ends of the rods, corner bars having longitudinal and transverse arms, the latter being mounted in and telescoping with the end bars, longitudinally disposed side bars in which the longitudinal arms of the corner bars are 50 mounted to telescope therewith, and means carried by the central portion of the framework for sustaining the same in the mouth of a grave, as and for the purpose specified.

6. A flower stand of the character described, comprising a supporting framework consisting of a central portion embodying a plurality of substantially parallel hollow longitudinal bars and pairs of transverse sleeves secured thereto, rods mounted at 60 their inner ends in the longitudinal bars and arranged to telescope therewith, transversely disposed end bars secured to the outer ends of the rods, corner bars having longitudinal and transverse arms, the latter being mounted 65 in and telescoping with the end bars, longitudinally disposed side bars in which the longitudinal arms of the corner bars are mounted to telescope therewith, and arms having their inner ends mounted in and telescoping with the respective sleeves and having a sliding connection with the corresponding side bars, said arms being adapted to be extended laterally beyond the side bars.

In testimony whereof I affix my signature 75 in presence of two witnesses.

EDWIN L. BERG. [L. S.]
